UNITED STATES PATENT OFFICE.

ANTONIO G. FERRARINI, OF CHICAGO, ILLINOIS, ASSIGNOR OF ONE-HALF TO CHICAGO BUILDERS SPECIALTIES COMPANY, OF CHICAGO, ILLINOIS, A CORPORATION OF ILLINOIS.

POLISHING-MACHINE.

1,180,992.

Specification of Letters Patent. Patented Apr. 25, 1916.

Application filed March 19, 1915. Serial No. 15,495.

To all whom it may concern:

Be it known that I, ANTONIO G. FERRARINI, a citizen of the United States, residing at Chicago, in the county of Cook and State of Illinois, have invented certain new and useful Improvements in Polishing-Machines, of which the following is a specification.

My invention relates to polishing or surfacing apparatus, and the principal object of the invention is to provide a simple and inexpensive machine for polishing or surfacing the walls or wainscoting of buildings, particularly walls or wainscoting made of or faced with terrazzo, concrete, mosaic work, or other like material.

A further object is to provide a machine of this sort consisting of a polishing tool, a motor, and a flexible shaft driven by the motor on which the tool is supported, whereby the tool may be moved over a very considerable area and turned in whatever position may be necessary without changing the position of the motor.

25 A further object is to provide a machine suitable for polishing the rounded surface or "cove base" which is employed, for sanitary reasons, in some buildings at the junction of a wall or wainscoting with a floor.

30 The invention has for further objects the other new and improved constructions, arrangements and devices relating to polishing or surfacing machines to be hereinafter described and claimed.

35 The invention is illustrated, in a preferred embodiment, in the accompanying drawings, wherein:

Figure 1 is a side elevation of the machine, Fig. 2, a longitudinal sectional view 40 taken through the tool holding shank and the outer end of the flexible shaft, and Fig. 3, a cross sectional view on line 3-3 of Fig. 2.

Like characters of reference designate 45 like parts in the several figures of the drawings.

Referring to the drawings, 10 designates a platform which is preferably mounted on wheels 11.

50 12 is a motor, of any desired type, supported on the platform 10. I have shown an electric motor but any other motor might be employed.

13 is a shaft mounted in brackets 14

on a framework 15 carried on the platform 10.

The polishing or surfacing tool consists preferably of a generally cylindrical body of carborundum or other suitable material 16, the outer end of which is rounded, as indicated at 17; the end being rounded particularly so that it will fit into the rounded surface or cove base 19 which frequently intervenes between the floor 20 and side wall 21 of a building. The surfacing tool is secured to a hollow tool-carrying element 22 through which extends a shaft 23. The tool is clamped between a boss 24 on the tool-carrying element 22, and a washer 25 and nut 26 on the end of shaft 23, the nut 70 and washer being located in a recess 27 in the end of the tool. Preferably a lead bushing 22a intervenes between the tool-carrying element 22 and the tool, this bushing affording a tight fit between the tool and 75 the carrying element. The latter is rigid with shaft 23.

The shaft 23 turns in ball bearings 28 in a casing 29, the bearings being located in heads 30, 31, forming part of the casing 29. 80 To the outside of the latter is secured, by means of screws 32, a strip 33 having an off-set projection 34 extending beyond the casing adjacent the surfacing tool 16. To the strip 33, 34 are secured studs 35 on 85 which are arranged hand grips 36 held on the studs by nuts 37 and formed with recesses 38 for spiral springs 39. The tool carrying shaft 23 is driven in any suitable manner from shaft 13, for example, by 90 flexible shafting consisting of shaft sections 40, 41, inclosed in hinged casings 42, 43, and connected to each other and with shaft 23 by pinion 44.

Operation: The truck 10 on which the apparatus is mounted may be moved from place to place in the room as the work progresses. Without moving the truck the flexible connection between the tool-carrying shaft and the driving shaft 13 on the truck allows the former very considerable amplitude of movement. The operator manipulates the tool by taking hold of the hand grips 36. Where springs 39 are interposed between the hand grips and the casing supporting the tool (which is the way I prefer to construct the machine), the work of manipulating the tool is facilitated both 100 105

in polishing flat surfaces and also the curved or cove base surface 19 between the wall and the floor since the tool will adjust itself to the surface on which it operates so that the 5 workman does not have to be so careful to keep the polishing surface of the tool in exact alinement with the wall or floor surface operated upon. Moreover, these springs reduce vibration. The rounding of the tool at 10 the end permits the polishing of a cove base such as indicated at 19 in Fig. 1. The surfacing tool 16 may be readily removed when worn out and a new tool substituted.

I claim:

- 15 1. In apparatus of the character described, the combination of a polishing tool, a tool-carrying shaft, a casing in which the shaft is revolubly mounted, a handle strip on the outside of the casing formed with an off-set 20 portion projecting beyond the casing adjacent the tool, handles at opposite ends of said strip, and means for revolving said shaft.
2. In apparatus of the character described, 25 the combination of a movable platform, a motor mounted on said platform, a shaft driven by said motor, flexible shafting connected with said driven shaft, a tool-carrying shaft driven by the flexible shaft, a casing 30 in which said tool-carrying shaft is revolubly mounted, handles on said casing, and a polishing tool on said tool-carrying shaft generally cylindrical in form and with its outer end rounded.
- 35 3. In apparatus of the character described, the combination of a movable platform, a motor mounted on said platform, a shaft driven by said motor, flexible shafting connected with said driven shaft, a tool-carrying 40 shaft driven by the flexible shaft, a casing in which said tool-carrying shaft is revolubly mounted, a tool holder rigid on said tool-carrying shaft formed with a

shoulder, a polishing tool generally cylindrical in form with its outer end rounded 45 and formed with a recess which is arranged upon said tool holder, means located within said recess for binding the tool between said shoulder and the end of the tool-carrying shaft, and handles on said casing.

4. In apparatus of the character described, the combination of a movable platform, a motor mounted on said platform, a shaft driven by said motor, flexible shafting connected with said driven shaft, a tool-carrying shaft driven by the flexible shaft, a casing 50 in which said tool-carrying shaft is revolubly mounted, a tool holder rigid on said tool-carrying shaft formed with a shoulder, a polishing tool generally cylindrical in form with its outer end rounded 55 and formed with a recess which is arranged upon said tool holder, means located within said recess for binding the tool between said shoulder and the end of the tool-carrying shaft, studs on said casing, handles slidably mounted on said studs, and springs interposed between the handles and the casing.

5. In apparatus of the character described, the combination of a movable platform, a 70 motor mounted on said platform, a shaft driven by the motor, a tool carrying shaft, a polishing tool having a generally cylindrical polishing surface mounted on the outer end of said tool carrying shaft so as 75 to revolve therewith, a casing in which the inner end of the tool carrying shaft is revolubly supported and which is provided with laterally extending means whereby the tool may be handled by the operator, and flexible 80 shafting operatively connecting said motor driven shaft with the tool carrying shaft.

ANTONIO G. FERRARINI.
